UNITED STATES PATENT OFFICE

RICHARD C. HUGHES, OF BEAVER DAM, WISCONSIN, ASSIGNOR OF ONE-HALF TO
ARTHUR W. LUECK, OF BEAVER DAM, WISCONSIN

ATTACHMENT FOR RURAL MAIL BOXES

Application filed June 5, 1929. Serial No. 368,631.

This invention relates to new and useful improvements in attachments for rural mail boxes.

One of the objects of my invention is the provision of an attachment for rural mail boxes wherein letters to be posted and collected by the rural delivery man can be quickly and easily removed from the mail box, and any letters or small mail articles can be so positioned as to be readily removed from the box by the owner, thus eliminating the necessity of going to considerable trouble to retrieve the mail from the interior of the box.

It is a well known fact that in a great many sections of the country, during the winter months, the rural postmen necessarily wear heavy gloves to protect their hands against the severe weather, and it is rather difficult to remove letters from the mail box without removing the gloves from the hands, and the case applies equally as well to the owner of the box when removing the mail from the box which has been left by the postman.

It is, therefore, one of the principal objects of my invention to provide an attachment for mail boxes which is so constructed and arranged that it will receive and retain letters and similar articles within the mail box and when the box is opened will be projected from the box so that they may be quickly and easily removed.

A further object of my invention is the provision of an attachment of the above character which resides in a slidable clamping member normally positioned within the mail box and has connection with the door of the mail box whereby the said clamping member is projected from the open end of the box when the door is opened and is returned to the interior of the mail box upon the closing of the door.

With the above and other objects in view, the invention consists in the novel features of construction, the combination and arrangement of parts hereinafter more fully set forth, pointed out in the claim and shown in the accompanying drawing wherein:

Figure 1 is a longitudinal sectional view

of the mail box illustrating the application of my invention;

Figure 2 is a transverse section on the line 2—2 of Figure 1; and,

Figure 3 is a detail section on the line 3—3 of Figure 1.

Referring to the drawing wherein I have illustrated the application of my invention, it will be noted that the numeral 1 indicates the conventional type of a rural delivery mail box having a hinged door 2 at the open end thereof which is retained in a closed position by means of yieldable catch members 3, said catch members having the usual means for applying a padlock or other lock for retaining the door in a closed position so that it can only be opened by the owner of the mail box or the postman.

My improved attachment comprises a slideable clamping member 4. This clamping member may be formed of two tapering plates 5 and 5' arranged in parallel relation and connected by means of rivet 6. It will be noted that the rivet 6 is arranged nearer the inner end of the plates than the outer end, so that the outer ends thereof may be easily forced apart as the plates are preferably formed of thin yieldable metal.

The outer ends of these plates are formed with outwardly curved portions 7 and 7' forming guides whereby letters or similar articles of mail may be readily forced between the two plates 5 and 5', the clamping action of the plates tightly gripping the letters or mail matter to hold them in position, as shown in Figure 1.

It will be noted that the clamping member 4 is preferably arranged in its normal position adjacent the open end of the mail box and is slidably mounted within the box by having the plate 5' formed with downwardly projecting feet 8, the lower ends of which are disposed at right angles and form a flat surface to ride upon the upper face of the bottom of the box.

The clamping member 4 is slidably mounted within guide arm 9 carried by one side of the mail box 1 and the member 4 is connected to an operating rod 10, the pivotal connection between the operating rod and the member 4

is arranged adjacent the inner end of the member 4, as shown at 11, while the other end of the rod 10 is pivotally connected to the door 2, as shown at 12. From this, it will be apparent that movement imparted to the door 2 will be readily conveyed to the slideable clamping member 4.

Normally, the member 4 is disposed within the housing adjacent the open end thereof, as shown in Figure 1, but when the door 2 is swung to an open position, as illustrated by dotted lines, the clamping member 4 is moved outwardly as shown by the dotted line position.

From this it will be apparent that when the mail box door 2 is swung to an open position, the clamping member 4 will be moved outwardly so that the outer end thereof projects beyond the end of the mail box, thus placing the clamping member in such position that the postman can readily remove any mail matter disposed between the plates 5 and 5' and can deposit between the plates any mail matter to be left in the box.

Preferably the clamping member 4 is used for receiving letters and small articles of mail which would necessitate difficulty in removing these articles from the large mail box, while rolls of newspapers and larger parcels can be deposited in the main box 1. It will be apparent that the postman can readily remove letters to be posted from the clamping member without the necessity of removing his gloves during winter weather, and the owner of the box can also readily remove any mail left in the clamping member.

I claim:

In combination with a mail box having a swinging door for closing one end thereof, a movable clamping member including plates arranged in opposed relation and tapering toward one end, means for connecting said plates adjacent the smaller end, one of said plates having downwardly projecting feet with laterally disposed lower ends to be slidably mounted upon the bottom of the housing, the larger ends of said plates being outwardly curved in opposed relation for receiving pieces of mail there between, a guide arm carried by the housing in which the plates are slidably mounted, a rod having pivotal connection with the smaller ends of the plates, and having its other end pivotally connected with the door whereby when the door is opened, the plates will be moved to a projected position with respect to the housing and disposed within the housing when the door is closed, said plates being formed of thin yieldable material for clampingly engaging objects disposed therebetween.

In testimony that I claim the foregoing I have hereunto set my hand at Beaver Dam, in the county of Dodge and State of Wisconsin, this 10 day of May, 1929.

RICHARD C. HUGHES.
